(57) **CLAIM**

The ornamental design for a mount accessory for phone grip, as shown and described.

DESCRIPTION

FIG. 1 is a bottom perspective view of a mount accessory for phone grip according to the present invention;

FIG. 2 is another bottom perspective view thereof;

FIG. 3 is a top perspective view thereof;

FIG. 4 is another top perspective view thereof;

FIG. 5 is a bottom view thereof;

FIG. 6 is a top view thereof;

FIG. 7 is a right side view thereof;

FIG. 8 is a left side view thereof;

FIG. 9 is a front view thereof; and,

FIG. 10 is a rear view thereof.

The broken lines are included for the purpose of illustrating portions of the mount accessory for phone grip that form no part of the claimed design.

1 Claim, 10 Drawing Sheets
